[57] **CLAIM**

The ornamental design for closet fitting for supporting a shelf and a hanger rod, substantially as shown.

DESCRIPTION

FIG. 1 is a front, right side, and top perspective view, reduced in size, of a closet fitting for supporting a shelf and hanger rod showing my new design;

FIG. 2 is a side elevational view thereof as seen from the right side;

FIG. 3 is a top plan view thereof;

FIG. 4 is a bottom plan view thereof;

FIG. 5 is an inverted side elevational view as seen from the left side of FIG. 1;

FIG. 6 is a front view thereof; and

FIG. 7 is a rear view thereof.

Fig. 1.Fig. 2.Fig. 3.Fig. 4.Fig. 5.Fig. 6.Fig. 7.
